AUTOMATIC MARKER BUOY

John Butka, Trumbull, and Andrew J. Nelson, Stratford, Conn., assignors to Butkin Tool and Manufacturing Corporation, Milford, Conn., a corporation of Connecticut

Filed May 28, 1963, Ser. No. 283,913
6 Claims. (Cl. 9—9)

This invention relates to an automatic marker buoy, and, more particularly, to such a buoy having means for automatic expulsion.

One of the problems encountered by outboard motor boat operators is that of losing the outboard motor over the side of the boat. It is difficult to retrieve such a motor when dropped alongside a dock or in other shallow spots. When the motor is dropped in deeper locations, it may be completely lost, either by reason of failure to snag it with grappling hooks or by inability to locate the exact position where the motor was lost.

Many prior art devices have been proposed to overcome these difficulties. These devices may be generally classified into two groups, those which float the motor and those which provide a marker buoy indicating the motor's position. One approach which is common to both classes is the use of inflatable balloons of various types which are actuated by compressed gas cylinders punctured upon submersion. In solving some problems, these devices create others. For example, any apparatus which is large enough to float an outboard motor will be quite large and bulky, even when not inflated. Also, the use of compressed gas cylinders for either floating the motor or inflating a marker buoy, presents problems. The compressed gas cylinders are not reusable. Accordingly, after an emergency a new compressed gas cylinder must be obtained before the device can be reset. Also with any container of compressed gas there is the possibility that over a long period of time the gases may leak out and render the device inoperative. Further, the inflatable bags or balloons may become leaky and defective over long periods during which they are stored in a folded position and subjected to temperature and humidity variations.

Another device which has been proposed for locating submerged motors is a marker buoy which is attached to a motor but is released by virtue of its buoyant force being greater than the force by which it is secured to the motor. The difficulties with devices of this type are two-fold. First, in order that the buoyant force exceed the force of attachment to the motor, the device must be relatively large so as to displace a considerable volume of water. Also, it will be apparent that a device of this type, unless it is quite large, will be only lightly secured to the motor and is therefore capable of being easily knocked loose.

Accordingly, it is the primary object of this invention to provide an improved outboard motor marker buoy. Other objects are to provide such a buoy which is noninflatable, which does not require the use of compressed gas cylinders, will be of small size, and which is forcibly ejected from the motor when the motor becomes submerged. Other objects, features and advantages will be apparent from the following description, the appended claims, and the figures of the attached drawing, wherein:

FIG. 1 illustrates the marker buoy of this invention as it appears mounted on an outboard motor;

FIG. 2 is a plan view of the apparatus of this invention partially cut away to illustrate its construction;

FIG. 3 is a cross section of the apparatus of FIG. 2, taken along the lines 3—3;

FIG. 4 is an enlarged detail view of the latch mechanism of the invention, and

2

FIG. 5 is an illustration showing the manner in which the buoy of the invention marks the location of a sunken motor.

FIG. 1 illustrates an outboard motor M secured to the transom T of a boat, the marker buoy apparatus B being mounted on the side of the motor. The figure also illustrates an alternative mounting of the marker buoy B' on the top of the motor.

The construction of one embodiment of the invention will be apparent from FIGS. 2 and 3. The illustrated embodiment includes a base plate 10 which is mounted directly to the outboard motor housing 12 by means of bolts 14 and 15 secured by nuts 16. Each of bolts 14 and 15 has a hexagonal head which is embedded in the base plate 10 to prevent twisting. However, bolt 15 also includes an upper extension 18 which has a longitudinally extending slot 20 and is transversely drilled to receive a pivot pin 22 through the slot 20 and has a somewhat similar drilled opening 24 positioned below slot 20. A slot 11 is provided in the base plate 10 from its approximate center to a point adjacent bolt 15. Base plate 10 also includes a pair of upwardly extending projections 26 having their lower edges positioned at an acute angle with the base plate 10. Projections 26 are positioned to either side of the bolt extension 18 and at the same end of the base plate 10. At the opposite end of the base plate 10 there is positioned a latch assembly L.

Mounted against the outer rim of base plate 10 is a cover 28 which includes a central circular wall 30 forming a central well. The wall 30 is cut away to form openings 32 which provide clearance around projections 26 and an opening 33 adjacent the latch assembly L. Both the circular wall 30 and the front portion of cover 28 are cut away to form a single slotted opening 34 extending from the well to the front of the enclosure. The cover 28 is secured to the base plate 10 by means of four screws 36 which extend upwardly through holes in the base plate 10 into suitably tapped matching holes in the cover.

One end of a retrieving hook arm 38 is drilled to receive pivot pin 22 and is positioned within the slot 20 contained in the upper extension 18 of bolt 15. A spring 40 is also coiled on pivot pin 22 and has one end inserted into drilled opening 24 in the upper bolt extension 18 and the other end inserted into a hole 42 in the retrieving hook arm 38. Spring 40 exerts a continuing pressure upwardly against the arm 38 tending to propel it to the position indicated by the numeral 38'. The retrieving hook arm 38 is inclined downwardly as illustrated in FIG. 3 and has a horizontal portion which is adapted to lie along the motor housing 12 when projecting through the slot 11 in base plate 10. The unpivoted end of the retrieving hook arm 38 carries a retrieving hook 44 having hook projections 441, 442. The hook 44 is in the shape of a flat plate and is positioned to lie along the upper surface of the base plate 10 when the right end of the hook arm, as seen in FIG. 3, is in the extreme downward position. The retrieving hook 44 also includes a drilled opening 46 and an upwardly projecting rib 48.

The marker buoy 50 which is used with this device is in the form of a hollow cylindrical spool having an upper flange 501 and a lower flange 502. The spool may be advantageously constructed of plastic or a light metal in order to keep its weight and size to a minimum. The buoy 50 is wrapped with a suitable line 52, one end of which is tied to the buoy and the other end to the retrieving hook by means of opening 46. The bottom of the marker buoy spool is provided with a slot 54 designed to engage rib 48 and thereby position the marker buoy relative to the cover 28. The marker buoy 50 is retained in the device by having its lower flange 502 inserted under the lower edges of the projections 26. The back portion

of the spool flange 502 is retained in place by catch 56 of the latch assembly L, as will now be explained.

Latch assembly L is most clearly illustrated in FIG. 4. The entire assembly is mounted on a separate base plate 58 which, in turn, is secured to the base plate 10. The base plate 58 is cut and shaped to include a pair of upwardly extending side frames 60, one of which has been omitted to disclose the mechanism. Supported between these side frames 60 are a latch pivot pin 62 and a release pivot pin 64. A generally L-shaped latch member 66 is rotatably mounted on the latch pivot pin 62 between the side frames 60 so as to partially project through opening 33 into the circular well. One leg of the L-shaped latch member 66 comprises the catch 56, while the other leg forms an ejector 68. Integral with latch member 66 is an upwardly extending latch plate 70. A spring 73 exerts a force against the latch member 66 and its included latch plate 70 tending to rotate them in a clockwise direction about latch pivot pin 62.

In FIGS. 2, 3 and 4 the latch member 66 is shown in the cocked position. In this position it will be seen that the upper end of latch plate 70 bears against the edge of a generally horizontal sear plate 72 which is connected, as by brazing or other suitable means, to a generally horizontal trigger lever 74. Trigger lever 74 is shaped to fit over the release pivot pin 64 and both it and the sear plate 72 are rotatable about the pivot pin. The right hand end of the trigger lever 74 is slotted and fits beneath the expanded head 76 of a stud 78 mounted atop an enclosed bellows 80. The slot allows clearance for relative movement between trigger cover 74 and stud 78, thereby compensating for expansion and contraction resulting from temperature changes. The trigger lever 74 is provided with a suitable spring (not shown) which maintains a slight force against lever 74 tending to rotate it in a counterclockwise direction about release pivot pin 64 so as to maintain the slotted end of lever 74 against head 76. With bellows 80 in the position illustrated, the sear plate 72 retains the latch plate 70 and its associated latch member 66 in the cocked position with the ejector 68 positioned below the flange 502 of the marker buoy 50 and with the catch 56 positioned above the flange to retain the buoy within the assembly.

After mounting the automatic marker buoy assembly on the motor housing the device is prepared for use by securing the free end of the line 52 from the marker buoy spool to the opening 46 in the retrieving hook 44. The retrieving hook is then depressed downwardly so that it lies at the bottom of the circular well formed by the wall 30. The marker buoy spool is then placed in position by inserting the forward edge of its lower flange 502 beneath the projections 26 and pushing down the opposite side of spool 50 so that lower flange 502 bears against the ejector 68 which is thereby rotated in a counterclockwise position until latch plate 70 is secured by the sear plate 72. The device is then ready for use.

If the motor should now be dropped overboard, the increase in pressure on the bellows 80 causes the bellows to compress thereby lowering the head 76. This depresses the right hand end of the trigger lever 74 and thereby lifts the edge of sear plate 72, releasing the latch plate 70. As pointed out, the latch member 66 is spring-loaded by means of spring 73 so that upon release it rotates in a clockwise direction, as shown by the dash-dotted lines in FIG. 4. A dual effect results from such rotation. The catch 56 releases the flange of the marker buoy 50 and the ejector 68 gives a positive upward displacement to the edge of the marker buoy, starting its displacement from the assembly. As the marker buoy 50 is thus released, it is completely displaced from the circular well in cover 28 by means of the counterclockwise rotation of the spring-loaded retrieving hook arm 38 which pivots about the pivot pin 22 and lifts the buoy from the circular well. At the same time, the retrieving hook arm 38 continues to rotate counterclockwise carrying with it the end of the line

52, until it is clear of the housing 28, as for example in the position 38' shown in FIG. 3.

The marker buoy 50 is now released from all restraints and rises to the surface of the water, as shown in FIG. 5, trailing behind it the line 52 secured to retrieving hook 44. It is important to note that the retrieving hook 44 and the hook arm 38 are connected directly to the motor housing 12 through the bolt 15. Accordingly, they are so positioned that an upward force on the retrieving hook arm 38 will lift the motor without damage to the relatively light-weight marker buoy base plate 10 or housing 28. Lifting of the motor may be achieved by either of two methods. If the motor is sufficiently light and if the line 52 is sufficiently strong, the motor may be retrieved directly by merely hauling in line 52. However, in many instances it may be necessary or desirable to retrieve the motor by means of a separate and stronger line. This is easily accomplished due to the shape of the retrieving hook 44 with its hook projections 441 and 442. The end of a retrieving line is secured to a ring of sufficient diameter to pass over these retrieving hook projections. The ring is then slipped over the upper end of the line 52 and is allowed to descend downwardly along the line until it has reached and snagged the retrieving hook 44 by one of its projections 441, 442. The motor may then be lifted by the retrieving line.

The apparatus is reset by winding the paid-out line back onto the spool. The retaining hook 44 is held down against the base 10 while the spool is inserted into the well with the front edge of flange 502 under projections 26. The back end is then depressed until flange 502 depresses ejector 68 of latch member 66 and repositions latch plate 70 against the edge of sear plate 72. The device is then ready for reuse.

For identification purposes, the marker buoy 50 may be provided on its upper surface with the plate bearing the name and address of the owner of the motor. This serves the dual function of identifying the motor while it is mounted thereon, as shown in FIG. 1, and also of identifying the owner of a sunken motor.

Many variations and modifications of this invention will be apparent to those skilled in the art which may be effected without departing from its true spirit and scope. Accordingly, the foregoing description it not to be construed as limiting, but as illustrative only. The invention is limited only by the scope of the following claims.

What we claim as new and desire to secure by Letters Patent of the United States is:

1. Automatically operable apparatus for indicating the position of a sunken object which comprises: a base adapted to be secured to such object; marker buoy means in the form of a substantially cylindrical spool having at least a first circular flange extending circumferentially around a first end thereof; at least one retaining lug means positioned adjacent said base to retain a first portion of the periphery of said first flange thereagainst; a generally L-shaped latch member adjacent a second portion of the periphery of said first flange, said latch member being pivotally secured to said base and having a first position wherein a first leg of said latch member is positioned above said flange and a second leg below said flange and a second position wherein said first leg is away from said flange and said second leg bears upwardly against said flange; spring means positioned to urge said latch member from its first to its second position; retaining means positioned to retain said latch member in its first position but actuatable to release said latch member; pressure responsive means connected to actuate said retaining means to release said latch member; and means for forcibly ejecting said marker buoy means from said base.

2. The apparatus of claim 1 wherein said pressure responsive means is a bellows.

3. The apparatus of claim 1 wherein said means for

ejecting comprises a lever arm having a first end pivotally mounted relative to said base and a second end positionable below said spool.

4. The apparatus of claim 3 wherein said spool includes a length of line having a first end secured thereto and a second end secured to the second end of said lever arm.

5. The apparatus of claim 4 wherein said second end of said lever arm includes hook-like snagging projections thereon.

6. The apparatus of claim 2 wherein said retaining means comprises an elongated trigger lever positioned substantially parallel to said base and rotatable about an axis parallel to said base and transverse to its longitudinal axis, a first end of said trigger lever being retained by said pressure-responsive means for movement there-

with and a second end being positioned to normally retain said latch member in its first position and to release said latch member upon activation of said pressure responsive means.
